(57) **CLAIM**

The ornamental design for a 3-button shuttle shift control, as
shown and described.

DESCRIPTION

FIG. 1 is a perspective view of a novel 3-button shuttle shift
control showing our new ornamental design;

FIG. 2 is a front view thereof;

FIG. 3 is a left side view thereof;

FIG. 4 is a right side view thereof;

FIG. 5 is a rear view thereof;

FIG. 6 is a top view thereof; and,

FIG. 7 is a bottom view thereof.

The broken lines shown throughout the drawing are for
illustrative purposes only and form no part of the claimed
design.
